UNITED STATES PATENT OFFICE.

EDMOND VERSTRAETE, OF BELLEVILLE, NEW JERSEY.

SOFA-BED.

1,383,501.

Specification of Letters Patent.

Patented July 5, 1921.

Application filed November 6, 1919. Serial No. 336,061.

To all whom it may concern:

Be it known that I, EDMOND VERSTRAETE, a citizen of the United States, residing at Belleville, in the county of Essex and State 5 of New Jersey, have invented certain new and useful Improvements in Sofa-Beds, of which the following is a specification.

My invention relates to improvements in sofa beds and has for its primary object to 10 provide a device of this character comprising comparatively few parts, said parts being simple in structure, easy to operate, and inexpensive to manufacture.

A further object of the invention lies in 15 the provision of a sofa having a movable back with an extension depending integrally therefrom, said extension being swung to a horizontal plane when the back of the sofa is moved downwardly over the seat.

20 A further object of the invention lies in the provision of a sofa having arm rests at each end forming pillows, a back pivotally connected with the rear of the sofa, and equipped with an integral extension, said 25 back capable of movement downwardly between the arm rests while at the same time the extension is elevated to a horizontal position being supported by folding legs pivotally attached thereto.

30 Other objects and advantages of the invention will be apparent during the course of the following description.

In the accompanying drawings forming a part of this specification and in which like 35 numerals are employed to designate like parts throughout the same,

Figure 1, is a front elevation of my improved sofa;

Fig. 2, is an end elevation with the extension in its folded position;

Fig. 3, is an end view showing my invention when used as a bed, and

Fig. 4 is a bottom fragmentary view showing the position of the folding legs 45 when the extension is collapsed.

In the drawings, wherein for the purpose of illustration I have shown a preferred embodiment of my invention, the numeral 5 designates the base or seat of the sofa 50 which is supported by a plurality of vertical extending legs 6 mounted upon the movable casters 7 to facilitate the moving of the sofa when desired. The sofa is of a somewhat rectangular shape and beneath 55 the base 5 a pair of compartments 8 are provided which receive the slideable draws

9 in the end thereof. Depending from the center of the face of the draw is a bracket 10, the lower end of which is bifurcated to receive the roller 11. A handle 12 is fixedly 60 attached to the draw approximately in its center to simplify the withdrawal of the same. The upper ends of the legs 6 extend a substantial distance above the base or seat 5 and have attached thereto longitudinally 65 extending arm rests 13 that are supported in an outwardly inclined position by the arcuate shaped bracket members 14. The seat 5 and arm rests 13 are furnished with upholstery material such as leather or other 70 serviceable tapestry.

The space between the two end legs 6 above the seat 5 is covered by the facing boards 15 that support the arcuate shaped brackets 14 and extend a substantial distance beyond the rear of the sofa. The auxiliary frame 16 forming the back of the sofa is provided with an integral extension 17 and is pivotally connected between the two facing boards 15 by the pivot 18 as clearly 80 shown in Fig. 2. Each end of the extension 17 is provided with a cushion 19 of a shape similar to that of the arm rests 13. When the auxiliary frame 16 is in a substantially vertical position the extension 17 is in close 85 contact with the rear of the sofa, being held in this position by the cotter pin 20 which passes through the opening 21 in the facing board and the opening 22 in the extension. The pin is attached to the facing board by a 90 cord 23 or other suitable means to prevent its loss. By removing the pin and swinging the auxiliary frame 16 downwardly between the ends of the sofa, the extension 17 will 95 be elevated to a horizontal plane as clearly shown in Fig. 3. In order that the extension will be substantially supported in this position, a pair of spaced bifurcated brackets 24 are rigidly attached to each end of the extension and support a pair of folding legs 100 25, the lower ends of which are braced by the rod 26. The cushions 19 and arm rests 13 form pillows for the bed. When in a collapsed position the legs 25 are folded longitudinally beneath the extension 17 being held 105 in position by the back of the sofa with which they contact.

In operation, the sofa when in a collapsed position is in appearance the same as any ordinary sofa and is rather attractive in design. For use as a bed, the cotter pin 20 is removed, so as to allow the auxiliary frame

16 having the extension 17 to move on the pivot 18 in the direction indicated in Fig. 2. The upper end of the auxiliary frame 16 is disposed between the arms of the sofa, and 5 elevates the bottom of the bed on a plane with the upper end of the legs 6. The extension 17 that extends in a horizontal plane from the rear of the sofa is supported by the folding legs 25 that will automatically swing 10 downwardly when the extension is moved to this position. The draws 9 that are slidably mounted in the compartments 8 may be used for storing the bed linen or any other desired purpose. Thus it is obvious from 15 the foregoing that a very novel and simple device of the above structure has been provided which is highly efficient in the accomplishment of its function and yet could be manufactured at a minimum cost.

20 It is to be understood that the form of my invention herewith shown and described is to be taken as a preferred example of the same, and that certain changes in the shape,

size, and arrangement of parts may be resorted to without departing from the spirit 25 of the invention or the scope of the subjoined claim.

Having thus fully described my invention, I claim:—

In combination with a main frame having 30 elevated rests at each end, facing boards parallel with the rests extending beyond the back of the frame, an auxiliary frame pivotally mounted between the facing boards having an integral extension, said auxiliary 35 frame capable of swinging to a horizontal position, lowering the upper end upon the main frame between the rests, and elevating the extension on a plane with the upper end, and means for supporting the extension. 40

In testimony whereof, I have affixed my signature in the presence of a witness.

EDMOND VERSTRAETE.

Witness:

THEODORE J. VERSTRAETE.
